UNITED STATES PATENT OFFICE.

WILLIAM E. HIGGINS, OF MILWAUKEE, WISCONSIN, ASSIGNOR TO FRANK HOLTON & COMPANY, OF CHICAGO, ILLINOIS, A CORPORATION OF ILLINOIS.

DESIGN FOR A CORNET.

48,319.

Specification for Design.

Patented Dec. 21, 1915.

Application filed March 11, 1915. Serial No. 13,754. Term of patent 14 years.

To all whom it may concern:

Be it known that I, WILLIAM E. HIGGINS, a citizen of the United States, residing at Milwaukee, in the county of Milwaukee and State of Wisconsin, have invented a new, original, and ornamental Design for a Cornet, of which the following is a specification, reference being had to the accompanying drawing, forming part thereof, and wherein—

Figure 1 is a side elevation illustrating my new design, and Fig. 2 is a bottom view of the same.

I claim:

The ornamental design for a cornet, as shown.

Milwaukee, Wisconsin, March 8th, 1915.

WILLIAM E. HIGGINS.
